Attorney

UNITED STATES PATENT OFFICE.

CHARLES G. MOLINE, OF WYANDOTTE, MICHIGAN.

WRENCH.

1,375,530.

Specification of Letters Patent. Patented Apr. 19, 1921.

Application filed November 11, 1919. Serial No. 337,114.

To all whom it may concern:

Be it known that I, CHARLES G. MOLINE, a citizen of the United States, residing at Wyandotte, in the county of Wayne and State of Michigan, have invented certain new and useful Improvements in Wrenches, of which the following is a specification.

This invention relates to wrenches of the handle lever grip type, and has for one of its objects to simplify the construction and increase the efficiency and utility of implements of this character.

Another object of the invention is to produce an implement of this character having means whereby the movable jaw is anchored in adjusted position relative to the stationary jaw without changing the relative positions of the operating handles.

With these and other objects in view, the invention accordingly consists in the features of construction, combination and arrangement of parts as will be clearly apparent as the description proceeds and then finally pointed out in the claims hereunto appended.

In the accompanying drawings,

Figure 1 is a side elevation with the operating grip handles or levers in closed position.

Fig. 2 is a side elevation with the operating grip handles or levers in open position. Fig. 3 is a cross section on the line 3—3 of Fig. 1.

Fig. 4 is a side elevation partly in section.

Fig. 5 is a detail of the stock illustrating the construction of the stop shoulders.

Similar reference characters indicate corresponding parts throughout the several views in the drawings.

The improved implement includes a stock 10 extended at one end into an operating handle or lever 11 and with a stationary jaw 12 at the other end, the jaw 12 being extended laterally at one side and the extended portion having a guideway therethrough indicated at 13. The body portion of the jaw 12 is preferably formed with a serrated face 14 to increase the grip, while the laterally extended part of the jaw is formed with a wire cutting member 15.

The movable jaw is represented at 16 and is formed with a bar or shank 17 which slidably engages through the guideway 13 of the stationary jaw, and is likewise provided with an opposing wire severing jaw 15'.

The shank 17 is formed with an extension 18 having its edges screw threaded as shown at 19.

An adjusting nut 20 engages the threaded extension, and is preferably cylindrical with its outer face milled or roughened to provide a gripping surface.

The side faces of the nut are in parallel relation and provide annular bearing faces. A bearing washer 21 surrounds the extension 18 and engages the nut, to receive the wear and impact when the wrench is actuated.

A grip applying lever 22 is extended at one end to form a handle 23 coöperating with the handle 11. The member 22 is U shaped transversely with the side portions extended laterally as shown at 24 to form cheek plates bearing upon opposite sides of the stock 10 and pivoted thereto as shown at 25. The cheek portions 24 are pierced by relatively large openings 26 to receive the outer portions of the nut 20.

Directed inwardly from opposite sides of the openings 26 are bearing lugs or projections 27 which contact respectively with the wear washer 17 and the opposite face of the nut, as shown in Figs. 1 and 2. The confronting faces of the washer and the nut, thus reduce the friction and likewise reduce the wear and prevent abrasion of the nut and washer.

The stock 10 is enlarged laterally as shown at 28 to form stop shoulders, while the cheek portions 24 of the member 22 are formed with stop lugs 29 which engage the stop shoulders when the members 11 and 22 are in closed position, to limit the inward movement, so that the handle members are spaced the same distance no matter how far apart the jaws 12 and 16 may be "set". The free ends 11 and 23 of the operating handles thus constantly occupy the same relative positions longitudinally of the implement, when in closed position.

The size of the hand grip portion of the implement is constant for all the adjustments of the jaws.

The coacting stops 28 and 29 also effectually prevent danger of "pinching" the fingers of the operator when the members 11 and 22 are closed.

The member 10 is increased in width as shown at 30 to enlarge the bearing portion 110 over which the cheek members 24 operate.

The implement can be constructed of any

required size and of any suitable material, but will preferably be of tempered steel, as light as possible consistent with the strains to which the implement will be subjected when in use.

What is claimed is:

1. A wrench of the class described comprising a stationary handle, a shank extending parallel with the handle and threaded at one end and having an outer jaw at the other end, a guide yoke secured to one end of the stationary handle and slidably receiving the shank, said yoke extended at one end into an inner jaw, a movable handle, spaced arms extending from the movable handle and pivoted to the stationary handle, and transversely apertured, and an adjusting nut engaging the threaded portion of the shank and extending through the openings in the arms and engaged by the contiguous walls of the same, whereby the shank is adjustable to control the space between the jaws and a positive grip produced by actuating the movable handle.

2. A wrench comprising a stationary handle, a shank extending parallel with the handle, a guide yoke secured to one end of the handle and slidably receiving the shank, a non-movable jaw carried by said end of the handle and the yoke, a movable jaw formed on one end of the shank, screw threads on the other end of the shank, an adjusting nut on the screw threaded end of the shank, a movable handle of channel formation receiving the shank and extending parallel with the stationary handle, spaced arms formed on the end of the movable handle and having openings to receive the nut, and said arms having their ends pivoted to the stationary handle, and projections on the walls of the openings in said arms and adapted to engage the nut for moving the movable jaw in the direction of the stationary jaw on the movable handle moving in the direction of the stationary handle.

In testimony whereof I hereunto affix my signature.

CHARLES G. MOLINE.
